[57] CLAIM

The ornamental design for a tire, as shown and de-
scribed.

DESCRIPTION

FIG. 1 is a perspective view of a tire, showing my new
design, it being understood that the tread pattern is
repeated throughout the circumference of the tire, the
opposite side being substantially the same as that shown;
and,FIG. 2 is a front elevation view thereof shown schemati-
cally by solid lines illustrating a fragmentary portion of
the tread pattern.FIG. 1

FIG. 2
